OLIVER S. JENNINGS, OF WILKINSBURG, PENNSYLVANIA, ASSIGNOR TO WESTINGHOUSE ELECTRIC AND MANUFACTURING COMPANY, A CORPORATION OF PENNSYLVANIA.

REVOLVING FAN.

1,261,131.

Specification of Letters Patent.

Patented Apr. 2, 1918.

Application filed January 6, 1915. Serial No. 789.

To all whom it may concern:

Be it known that I, OLIVER S. JENNINGS, a citizen of the United States, and a resident of Wilkinsburg, in the county of Allegheny and State of Pennsylvania, have invented a new and useful Improvement in Revolving Fans, of which the following is a specification.

My invention relates to revolving fans, 10 and it has special reference to gyratory electric fans that are adapted to turn on an axis of rotation while simultaneously and automatically turning around an external axis of revolution.

15 One object of my invention is to provide a gyratory fan of simple, compact and durable construction which shall be provided with positively actuated mechanical means for effecting the rotation of the fan support by power derived from the rotating shaft that carries the fan blades.

20 Another object of my invention is to provide a fan of the above-indicated character which can be readily adjusted to deliver air, 25 either horizontally or at various angles of inclination, without disengaging the gearing which causes the revolution of the fan structure.

In the accompanying drawings, Figure 1 30 is a side view, mainly in elevation but partly in section, of a revolving fan constructed in accordance with my invention; and Fig. 2 is a side elevational view, with parts in section, of a modified form of device embodying my invention. In both of the structures 35 shown in the drawing, means are provided for causing the structure which carries the fan motors to turn about an axis of revolution by the frictional engagement of one or 40 more motor-driven rotating members with a circular stationary track. Means are also provided for permitting the angle at which the fans deliver air to be varied to a considerable degree without disengaging the 45 frictional driving means.

The structure shown in Fig. 1 comprises two fan motors 1 and 2 that are pivotally mounted upon arms 3 and 4 of a rotatable bracket member 5. The bracket member 5 50 is rotatably suspended from a hanger rod 6, to the lower end of which is rigidly attached a casing or hood member 7 provided with a horizontal transverse partition 8, in which is formed a screw-threaded central 55 opening 9 adapted to receive the upper end

of a sleeve 10. The bracket member 5 is provided with a central vertical opening through which the sleeve 10 extends, and ball bearings 11 are disposed in suitable ball races between the bracket member 5 and the sleeve 10. A bottom casting 13, which conforms in external contour to the shape of the bracket member 5, is attached to the lower end of the sleeve 10, and lamp sockets 14 may, if desired, be attached to the casting 13 in order that the structure may serve as an electrolier.

The hood member 7 is provided with four equally-spaced slots 15 that are adapted to receive and guide the outer ends of the four 70 arms of a spider 16. To the ends of the arms of the spider 16 is attached, by means of screws 17, an annular member 18 provided with a groove 19 which serves as a stationary friction track. The spider 16 is 75 provided with an internally threaded central opening that receives a screw-threaded sleeve 20, which is inclosed within the sleeve 10 and is provided with a flange 21 to rest upon the upper end of the sleeve 10. To the lower 80 end of the sleeve 20 is secured a knob 22 which prevents vertical movement of the sleeve 20 and by means of which the sleeve 85 may be manually turned. When the sleeve 20 is so turned, the screw engagement between the sleeve and the spider 16 causes the spider, and consequently the annular member 18, to move vertically, guided by the slots 15.

The fan motors 1 and 2 may be of any 90 well-known type, and the details of their construction will therefore not be described. To the inner end of one or both of the armature shafts 25 of the fan motors is secured a worm 26 meshing with a worm wheel 27 95 that is secured to the upper end of a short shaft 28 which carries, at its lower end, a ball 29 that is adapted to engage the annular track 19 formed in the member 18. Since the centers of gravity of the fan motors are 100 beyond their points of pivotal attachment to the bracket arms, the fan motors tend to rotate outwardly, and the balls 29 are thereby pressed tightly against the track 19.

Electric energy may be supplied to the 105 fan motors and to the lamp sockets 14 in any convenient manner. As shown in the drawing, brushes 30 and 31 rest upon corresponding slip rings 32 and 33 from which current is conducted to the motors through 110

conductors 34 and 35. The electric circuits may be controlled in any suitable manner, for example, by means of a switch device 36 operated by means of a button 37 through 5 an intermediate rod 38 inclosed within the sleeve 20.

In the operation of the fan constructed in the manner shown, the rotation of the armature shaft 25 is communicated through the 10 worm 26 and the worm wheel 27 to the shaft 28 and the balls 29, which are in frictional engagement with the track 19, to cause the bracket 5, together with the fan motors, to rotate around the hanger 6. The tilt of the 15 fans may be readily varied by turning the knob 22 and thereby moving the track 19 vertically in the slots 15. Since the motors are so pivoted that they tend to swing outwardly about their pivots, they will conform 20 automatically to changes in the position of the track 19. One or both of the motors may be provided with the frictional driving means described above, but I prefer that only one motor shall be so equipped, the 25 other being provided with a rod 28 and a ball 29 that serve to maintain this motor at the same inclination as the driving motor.

The modified device shown in Fig. 2 differs from that shown in Fig. 1 in that 30 means are provided for varying the speed of rotation of the bracket 5. As in the preceding modification, each of the armature shafts 25 of the fan motors is provided with a worm 26 that meshes with a worm wheel 35 secured to the upper end of a short counter-shaft 40 which is mounted in bearings in a casing 41 attached to the rear end bell of the motor. The lower end of the counter-shaft 40 carries a worm 42 to mesh with a worm 40 wheel 43 that is held between suitable ball bearings 44 in the casing 41 and is slidably keyed to a splined shaft 45 which carries, at its inner end, a ball 46.

The annular member 18, in this modification of my device is provided with an outwardly extending horizontal track 47 against which the balls 46 are adapted to press in order to turn the bracket 5 around the support 6, as in the first modification described above. The speed at which the bracket is rotated may be varied by sliding the splined shafts 45 with respect to the worm wheel 43 and thereby causing the balls 46 to take different radial positions 55 with respect to the track 47. The shafts 45 may be secured in their adjusted positions by means of collars 48 which are fastened in place by means of set screws 49. The ends of the shafts 45 opposite to the balls 60 46 may be threaded to receive nuts 50 which prevent the shafts 45 from being entirely removed from engagement with the worm wheel 43. If desired, the ends of the shafts 45 may be screw-threaded sufficiently to enable the nuts 50 to be screwed into engage-

ment with the casing 41 and thus prevent any longitudinal movement of the shafts. This is not necessary, however, since the frictional engagement between the track 47 and the balls 46 tends to force the shafts 70 45 lengthwise away from the center of revolution of the bracket 5.

As in the modification shown in Fig. 1, the annular member 18 carrying the track 47 may be vertically moved in the slots 15 75 by manipulating the knob 22. It will be evident that the second modification of my device is capable of many adjustments with respect to the tilt of the fan motors and the speed at which the supporting bracket 80 revolves, and that either of these adjustments may be made without affecting the other by properly positioning the shafts 45 and the track 47.

The structures which I have shown and 85 described may be variously modified without departing from the principles of my invention, and it is therefore to be understood that my invention comprehends all such structural changes and modifications 90 as fall within the scope of the appended claims.

I claim as my invention:

1. The combination with a rotatable support, of a motor pivotally mounted on the 95 said support, and friction gearing driven by the said motor for rotating the said support, the said gearing being held in frictional engagement as the said motor rotates under the influence of gravity about its 100 pivotal axis.

2. The combination with a rotatable support, of a motor pivotally mounted on the 105 said support, a normally stationary track disposed adjacent to the said support, and a friction member driven by the said motor and adapted to engage the said track for rotating the said support as the said motor rotates under the influence of gravity about its 110 pivotal axis.

3. The combination with a rotatable support, of a motor mounted on the support, a normally stationary track disposed adjacent to the said support, a friction member driven by the said motor and adapted to engage the 115 said track for rotating the said support, and means for adjusting the position of the said track.

4. The combination with a rotatable support, of a fan motor pivotally mounted on 120 the said support, a normally stationary track disposed adjacent to the said support, a shaft driven by the said fan motor, and a rotatable friction member carried by the said shaft and adapted to frictionally engage the said track for rotating the said support, as the said motor rotates under the influence of gravity about its pivotal axis.

5. The combination with a rotatable support, of a fan motor pivotally mounted on 130

the said support, a normally stationary track disposed adjacent to the said support, a shaft driven by the said fan motor, and a ball carried by the said shaft and adapted to engage the said track for rotating the said support, as the said motor rotates under the influence of gravity about its pivotal axis.

6. The combination with a rotatable support, of a fan motor pivotally mounted on the said support, a normally stationary track disposed adjacent to the said support, a friction member driven by the said fan motor and adapted to engage the said track, and screw-operated means for manually adjusting the position of the said track, and for causing pivotal movement of said motor on said support.

7. The combination with a rotatable support, of a fan motor pivotally mounted on the said support, a normally stationary track disposed adjacent to the said support, a friction member driven by the said fan motor and adapted to engage the said support, means for supporting the said track, screw-operated means for manually adjusting the position of the said track support, and means for varying the radial position of the said friction member with respect to the said track.

8. The combination with a rotatable sup-

port, of a motor mounted on the said support, a normally stationary circular track disposed adjacent to the said support, a friction member driven by the said motor and adapted to engage the said track, means for adjusting the position of the said track, and means for varying the radial position of the said friction member with respect to the said track.

9. The combination with a rotatable support, of an electric fan motor mounted on the said support, a normally stationary circular track disposed adjacent to the said support, a worm axially associated with the armature shaft of the said motor, a worm wheel meshing with the said worm and secured to a counter shaft, a worm formed on the said counter shaft and meshing with a worm wheel slidably keyed to a splined shaft, a friction member carried by the said splined shaft and adapted to engage the said track, and means for securing the said splined shaft in position with respect to the said worm wheel.

In testimony whereof, I have hereunto subscribed my name this 30th day of Dec., 1914.

OLIVER S. JENNINGS.
